PRIVACY FENCE

John S. Case, Towson, Md., assignor to Anchor Post Products, Inc., Baltimore, Md., a corporation of New Jersey

Filed Mar. 15, 1962, Ser. No. 69,276

Term of patent 14 years

(Cl. D28—1)

FIG. 1

FIG. 2

FIG. 1 is a perspective view of a section of a privacy fence with staggered panels incorporating my new design; FIG. 2 is a perspective view of a typical panel;

FIG. 3 is a perspective view of a section of a privacy fence within line panels; and

FIG. 4 is a top view of the fence sections of FIGS. 1 and 3.

What I claim is:

The ornamental design for a privacy fence, as shown and described.
